UNITED STATES PATENT OFFICE

104,454

DESIGN FOR A CHEESE SLICER

Joseph William Koch, Santa Fe, N. Mex.

Application March 12, 1937, Serial No. 68,143

Term of patent 7 years

To all whom it may concern:

Be it known that I, Joseph William Koch, a citizen of the United States, residing at Santa Fe, in the county of Santa Fe and State of New Mexico, have invented a new, original, and ornamental Design for a Cheese Slicer, of which the following is a specification, reference being had to the accompanying drawing, forming part thereof.

I claim:

The ornamental design for a cheese slicer as shown.

JOSEPH WILLIAM KOCH.
